UNITED STATES PATENT OFFICE.

RAYMOND E. BEEGLE, OF EAST ST. LOUIS, ILLINOIS.

DESIGN FOR A TIRE.

Application filed August 13, 1924. Serial No. 10,442. Term of patent 7 years.

To all whom it may concern:

Be it known that I, RAYMOND E. BEEGLE, a citizen of the United States, residing at East St. Louis, in the county of St. Clair and State of Illinois, have invented a new, original, and ornamental Design for a Tire, of which the following is a specification, reference being had to the accompanying drawing, forming a part thereof.

I claim:

The ornamental design for a tire, as shown.

RAYMOND E. BEEGLE.
